UNITED STATES PATENT OFFICE

167,690

COSMETIC CONTAINER

Robert Brown Hopgood, Cheshire, Conn., assignor to The Eyelet Specialty Company, Waterbury, Conn.

Application February 6, 1952, Serial No. 18,419

Term of patent 14 years

(Cl. D86—10)

To all whom it may concern:

Be it known that I, Robert Brown Hopgood, a citizen of the United States of America and resident of Cheshire, county of New Haven and State of Connecticut, have invented a new, original, and ornamental Design for a Cosmetic Container, of which the following is a specification, reference being had to the accompanying drawing, forming parts hereof.

Fig. 1 is a front elevational view of a cosmetic container, showing my new design, and with the stick-receptacles in place;

Fig. 2 is a side elevational view of the same;
Fig. 3 is a top plan view of the same;

Fig. 4 is a vertical sectional view through the holder, with the stick-receptacles removed;

Fig. 5 is a front elevational view of the holder with the stick-receptacles removed, and

Fig. 6 is a sectional view taken on the line 6—6 of Fig. 4, looking in the direction of the arrows.

I claim:

The ornamental design for a cosmetic container, substantially as shown.

ROBERT BROWN HOPGOOD.
